CLAIM

The ornamental design for a “caulk gun trigger with caulk plug stowage” as shown and described.

DESCRIPTION

FIG. 1 is a rear perspective view of a caulk gun trigger with caulk plug stowage showing our new design;

FIG. 2 is a bottom rear perspective view thereof;

FIG. 3 is front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is a cross-sectional view thereof, taken along line 9-9 of FIG. 3;

FIG. 10 is a cross-sectional view thereof, taken along line 10-10 of FIG. 5;

FIG. 11 is an enlarged partial view of the area indicated as 11 in FIG. 1;

FIG. 12 is an enlarged partial view of the area indicated as 12 in FIG. 2;

FIG. 13 is an enlarged partial view of the area indicated as 13 in FIG. 8;

FIG. 14 is an enlarged partial view of the area indicated as 14 in FIG. 9;

FIG. 15 is an enlarged partial view of the area indicated as 15 in FIG. 10; and,

FIG. 16 is a bottom perspective view thereof, wherein a caulk plug is shown in a position of stowage.

The aspects of the caulk gun trigger illustrated in broken line form, are not part of the claimed design. The broken line showings of the caulk gun and the caulk gun plug are provided for purposes of environment and form no part of the claimed design. The dot-dash broken line along the perimeter of the trigger defines the boundaries of the claimed design.
